Primary Examiner — Cynthia Underwood(74) *Attorney, Agent, or Firm* — Morrison & Foerster LLP(57) **CLAIM**

The ornamental design for a hand-held shower bracket, as shown and described.

DESCRIPTION

FIG. 1 is a front and right side perspective view of a hand-held shower bracket showing the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The features shown in broken lines form no part of the claimed design.
